J. SOSS.
SPRING CATCH DEVICE.
APPLICATION FILED SEPT. 20, 1919.

Patented Aug. 31, 1920.

Inventor
Joseph Soss
By his Attorney

Edgar A. Sto.

UNITED STATES PATENT OFFICE.

JOSEPH SOSS, OF NEW YORK, N. Y.

SPRING-CATCH DEVICE.

1,351,072.

Specification of Letters Patent. Patented Aug. 31, 1920.

Application filed September 20, 1919. Serial No. 325,111.

To all whom it may concern:

Be it known that I, JOSEPH Soss, a citizen of the United States, and residing at New York, in the county of New York and State 5 of New York, have invented certain new and useful Improvements in Spring-Catch Devices, of which the following is a specification, such as will enable those skilled in the art to which it appertains to make and 10 use the same.

This invention relates to spring catch devices and particularly to devices of this class designed for use in connection with the hoods and curtains of automobiles for supporting such hoods and curtains in connection with the framework of a hood as well as the body of an automobile, and also for securing the separate parts of the hood and the separate curtains thereof together, 15 and the object of the invention is to provide a spring catch device of the class and for the purpose specified which is simple in construction and operation and strong and durable in use and which will securely hold the 20 separate parts of the hood together against accidental displacement and also readily facilitate the attachment and detachment of the separate parts of said hood whenever desired; and with this and other objects in 25 view the invention consists in a device of the class and for the purpose specified, constructed and operated as hereinafter described and claimed.

The invention is fully disclosed in the 30 following specification, of which the accompanying drawing forms a part, in which the separate parts of my improvement are designated by suitable reference characters in each of the views, and in which:—

40 Figure 1 is a plan view of one of my complete spring catch devices and indicating the method of its use;

Fig. 2 a partial section on the line 2—2 of Fig. 1;

45 Fig. 3 a partial section on the line 3—3 of Fig. 2;

Fig. 4 a partial section on the line 4—4 of Fig. 2 but showing a modified form of one of the separate parts of the device; and,

50 Fig. 5 a view looking in the direction of the arrow 5 of Fig. 4.

In Figs. 1 to 3 inclusive, I have shown one

form of catch device which consists of two separate parts 6 and 7, the part 6 being in the form of an eyelet while the part 7 is in 55 the form of a stud. The part 6 is adapted to be secured to a part 8 of a hood, or the curtains or separate parts of said hood, while the part 7 is adapted to be secured to the body or framework of the automobile 60 which is indicated at 9 in dotted lines in Figs. 1 and 2.

The part 6, as previously stated, is in the form of an eyelet and comprises an inner annular beaded portion 10 in which is secured a rod 11 consisting of a transverse central portion or bar 12 and oppositely directed arc-shaped portions 13 which fit within the annular beaded portion 10 of the part 6. The arc-shaped portions 13 pass 70 through cut-out portions 14 on the opposite sides of the beaded portion 10 as illustrated in Figs. 1 and 3. The part or eyelet 6 is also provided with an annular compressed portion 15 outwardly of the beaded portion 75 10 which serves to secure the eyelet to the part 8 of the hood, as clearly illustrated in Fig. 2 of the drawing.

The part or stud 7 consists of a cylindrical and hollow head portion 16 having an 80 enlarged base portion 17, which is hexagonal in form as shown at 18 in Fig. 2, and provided below the hexagonal portion with an enlarged beaded portion 19, having an inwardly directed flange 20. The enlarged 85 base portion 17, or the separate parts 18, 19 and 20 thereof, serve to secure the hexagonal head 21 of a wood screw 22 therein. The cylindrical head portion 16 is provided with a transverse slot or aperture 23 through 90 which the bar 12 of the part or eyelet 6 is adapted to pass in connecting the separate parts 6 and 7 together. A spring member 24 is mounted within the cylindrical head 95 16 and above the hexagonal head 21 of the wood screw 22. The spring member 24 is made from a strip of sheet metal bent centrally to form an enlarged central and inner loop 25 and two oppositely arranged outer loops 26, and oppositely arranged spring end portions 27 which are preferably spaced apart to a slight extent to permit of the free action of the loop members 26 within the cylindrical head portion 16. The spring 100

member 24 is held against rotation in the cylindrical portion 16 by depressions 28 formed at the bottom part of the cylindrical portion 16, as clearly shown in Fig. 3 of the drawing. These depressions will hold the spring member 24, or the spring loop members 26 thereof in a line parallel with the rod or cross bar 12 of the part 6, but it will be understood that I am not necessarily limited to the holding of the spring member 24 in a fixed position, as this spring member may, if desired, rotate within the cylindrical portion 16.

In Figs. 4 and 5 of the drawing, I have shown a slight modification of the construction shown in Figs. 1 to 3 inclusive, in which the part 7 is secured to a curtain 29, or part of the hood of an automobile, and in accomplishing this result the cylindrical portion 16 of the part 7 is provided with a base flange 30 which is cut out at intervals to form downwardly directed prongs 31, four of which are preferably employed. In connecting the part 7 with the curtain 29, the prongs 31 are passed through the curtain 29 and through apertures 32 in a disk or washer 33 and said prongs are then bent inwardly to secure the part 7 to the curtain 29.

With the construction shown in Figs. 4 and 5 it will be seen that the part 7 of the spring catch device will be securely held in connection with the curtain 29 with the spring 24 therein, and the curtain 8 or other part of the hood provided with a part or eyelet 6 may be connected therewith.

From the foregoing it will be seen that by the construction shown in Figs. 1 to 3 inclusive, I provide a spring catch device which is used for detachably mounting a curtain or part of a hood in connection with the framework of the car, while in Figs. 4 and 5 of the drawing, I have shown a form of spring catch device used in connecting the separate parts or curtains of the hood, and while I have shown certain details of construction for carrying my invention into effect, it will be apparent that my improvement is not necessarily limited to such details, and various changes therein and modifications thereof may be made, within the scope of the appended claims, without departing from the spirit of my invention or sacrificing its advantages.

Having fully described my invention, what I claim as new and desire to secure by Letters Patent, is:—

1. A device of the class described comprising an eyelet provided with a cross bar centrally of the aperture of said eyelet, a stud member comprising a hollow portion and a spring in said hollow portion, said hollow portion being provided with a transverse aperture through which the cross bar

of the eyelet is adapted to pass and operate 65 in connection with the spring within said hollow portion.

2. A spring catch device of the class described comprising an eyelet member provided with a transverse cross bar and a stud 70 member comprising a hollow cylindrical portion provided with a transverse aperture, and a spring within said cylindrical portion and provided with two spring loop members adapted to operate in connection 75 with the transverse cross bar of the eyelet member for detachably connecting the same with said stud member.

3. A spring catch device of the class described comprising an eyelet member provided with a transverse cross bar, a stud member comprising a hollow cylindrical portion provided with a transverse aperture, a spring within said cylindrical portion and provided with two spring loop members 85 adapted to operate in connection with the transverse cross bar of the eyelet member for detachably connecting the same with said stud member, and means on said stud member for connecting the same with a suitable support.

4. A spring catch device of the class described comprising an eyelet member, a transverse rod mounted centrally of the aperture of said eyelet and the end portions 95 of which pass into and are secured between the side portions of the eyelet member, a stud member comprising a cylindrical head portion provided with a transverse aperture, a spring device mounted in said cylindrical portion and comprising an inner loop member and two outer spring loop members adapted to operate in connection with the transverse rod of the eyelet member, and means for securing said stud member in 105 connection with a suitable support.

5. A device of the class described comprising an eyelet and a stud, said eyelet being provided with a transverse member and said stud being provided with an apertured portion adapted to pass into said eyelet, and said stud being provided with a spring member adapted to operate in connection with the transverse member of the eyelet for holding said parts together.

6. A device of the class described comprising an eyelet and a stud, said stud being provided with a part adapted to pass into said eyelet, tensional means in said stud, and means on said eyelet projecting into the 120 aperture therein and adapted to operate in connection with said stud and the tensional means thereof in passing said stud into the aperture of said eyelet for holding said parts together.

7. A device of the class described comprising an eyelet, means for securing said eyelet to a suitable support, a stud having

an apertured portion, a spring mounted in
said stud, and means in said eyelet adapted
to pass through the apertured portion of
said stud and to operate in connection with
5 said spring in the operation of passing the
stud into said eyelet for securing said parts
together.

In testimony that I claim the foregoing

as my invention I have signed my name in
presence of the subscribing witnesses this 10
19th day of September, 1919.

JOSEPH SOSS.
